Primary Examiner — Jennifer L Rempfer*Assistant Examiner* — Arun Salil Kamat(74) *Attorney, Agent, or Firm* — Andrus Intellectual Property Law, LLP(57) **CLAIM**

The ornamental design for a product display panel as shown and described.

DESCRIPTION

FIG. 1 is a front perspective view of a product display panel according to our new and ornamental design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dot-dash broken lines represent the boundaries of the claimed design and form no part of the claimed design. The broken lines outside of the boundaries represent portions of the product display panel that form no part of the claimed design.

1 Claim, 4 Drawing Sheets(56)
